UNITED STATES PATENT OFFICE.

CHARLES J. NASH, OF CHICAGO, ILLINOIS, ASSIGNOR TO UNIVERSAL DRAFT GEAR
ATTACHMENT CO., A CORPORATION OF ILLINOIS.

DRAFT-ARM.

1,122,530.

Specification of Letters Patent.

Patented Dec. 29, 1914.

Application filed January 16, 1914. Serial No. 812,384.

To all whom it may concern:

Be it known that I, CHARLES J. NASH, a citizen of the United States, and resident of Chicago, county of Cook, and State of Illinois, have invented certain new and useful Improvements in Draft-Arms, of which the following is a specification and which are illustrated in the accompanying drawings, forming a part thereof.

10 The invention relates to draft arms for railway cars, and is an improvement on the draft arm forming the subject of my pending application Serial No. 789,445, filed September 12th, 1913.

15 The object of the present invention is to provide the draft arm with means for bearing directly upon both of the vertical faces of a transom or bolster, in connection with means for resisting upward movement of 20 the rearward end of the arm.

The invention is exemplified in the accompanying drawings, and is hereinafter described.

25 In the drawings, Figure 1 is a side elevation of the improved draft arm as applied to a railway car; Fig. 2 is a detail plan view of the center sills of a car with the improved draft arms applied thereto, the latter being shown partly in section; and Fig. 30 3 is a view in perspective of a tie and buffer casting applied to the rear ends of the draft arms proper.

35 In the drawings, the center sills of a car are represented at 10 and 11, and the end sill thereof at 12.

The draft arm, generally represented by the numeral 13, is a casting, one being attached to each of the center sills and, to this end, being provided with a lateral 40 flange 14 bearing against the bottom of the sill and an upstanding flange 15 bearing against the inner face thereof. Each arm is also provided with a pair of draft shoulders 16, 17, for engagement by the usual 45 followers of a draft gear, and in the construction illustrated the arm is provided with an aperture 18 between the draft shoulders to accommodate the transverse rod of the Cardwell type of gear. Each 50 draft arm is also provided with a rearwardly facing shoulder 19 for bearing against the body bolster 20 of the car, and with a rearward extension 21 which arches over the bolster and extends some distance 55 back thereof. So far as thus described the

arm is substantially identical with that of my previous application. The present improvement consists in providing the extension 21 with a depending lug 22 which bears against the rearward face of the bolster 20, 60 and a casting 23 which is applied and riveted to the under faces of the extensions 21 of the two draft arms, bears against a downwardly projecting lug 24 at the rearward end thereof, and also bears against the rearward face of the bolster 20, the forward end of the extension being of sufficient depth to engage the lower portion of the bolster. The casting 23 is of sufficient width to extend under the sills 10, 11, to which it is secured by means of bolts 25, 26. The rear end of the casting is flattened and abuts against timbers 27 located immediately below the two center sills and which, in accordance with the showing in my previous 75 application, may extend to the farther end of the car and similarly engage the draft arms there located.

By the construction illustrated and described provision is made for transmitting 80 stresses due to tractive effort directly to the bolster 20 through the lugs 22 and the lugs 24 and casting 23. Bounding stresses are transmitted directly to the bolster 20, and through it and the casting 23 to the timbers 27. The casting 23 ties the two draft arms together and, bearing upwardly 85 against the center sills, resists the tendency to upward movement and strengthens the rearward extensions 21.

I claim as my invention—

1. A draft arm for railway cars having a shoulder for abutting against the forward face of a bolster, and extension for arching over the bolster, such extension being provided with a forwardly facing shoulder for engaging the rearward face of the bolster, and a lateral flange for the attachment of a plate for engaging the lower face of a car sill.

2. A pair of draft arms for a railway car, each having a rearward extension for arching over and engaging the rearward face of a bolster of the car, and a member secured to the arm extensions and adapted 105 to bear upwardly against the center sills of a car and against the rearward face of the bolster.

3. A draft arm for railway cars having a shoulder for engaging the front face of a 110

- bolster, and a rearward extension for arching over the bolster, such extension having a shoulder for bearing against the rearward face of the bolster, and a member bearing
- 5 upwardly against the rearward extension secured thereto by vertical attaching members and adapted to engage the rear face of the bolster and the under faces of the sills of the car.
- 10 4. A pair of draft arms for a railway car each having a rearward extension for arching over a bolster of the car and being provided with a depending lug, and a member secured to the arm extensions and adapted

to bear against the depending lugs of the 15 arms, upwardly against the center sills of a car and against the rearward face of the bolster.

5. A draft arm for railway cars having a rearward extension for arching over the 20 bolster of a car, such extension having a depending lug, and a member fitting between such lug and the bolster.

CHARLES J. NASH.
